UNITED STATES PATENT OFFICE

JOHN W. H. HAMILTON, OF NEW YORK, N. Y.

DESIGN FOR A COMBINATION MAGAZINE AND BOOK RACK OR THE LIKE ARTICLE

Application filed October 27, 1932. Serial No. 45,594. Term of patent 7 years.

To all whom it may concern:

Be it known that I, JOHN W. H. HAMILTON, a citizen of the United States, residing at New York, in the county of New York and State of New York, have invented a new, original, and ornamental Design for a Combination Magazine and Book Rack or the Like Article, of which the following is a specification, reference being had to the accompanying drawing, forming part thereof.

Figure 1 is a front elevation of the combination magazine and book rack or the like article showing my new design.

Figure 2 is a rear elevation thereof.

Figure 3 is an end elevation of one side of the rack.

Figure 4 is a similar view of the other side thereof, and

Figure 5 is a top plan view.

I claim:

The ornamental design for a combination magazine and book rack or the like article, as shown.

JOHN W. H. HAMILTON.
